PIPE WORKING MACHINE

William A. Phllis, Warren, Ohio, assignor to
Beaver Pipe Tools, Inc., Warren, Ohio, a corpora-
tion of Ohio

Application March 1, 1938, Serial No. 193,311

18 Claims.

(Cl. 10—89)

This invention relates to a power machine primarily for performing operations on pipes, such as threading and cutting operations.

The machine is of the type shown and described in Patent No. 2,079,179, to R. B. Pealer, assigned to my assignee, Beaver Pipe Tools, Inc., which has a power operated chuck and a slideable carriage carrying suitable tools, for example, a threader and a cutter.

One of the objects of the invention is to simplify the construction of such a machine, rendering it more compact, with a consequent reduction in weight and cost of manufacture. Another object is to so arrange the motor and its driving mechanism that the motor may be mounted beneath the carriage, and at the same time be thoroughly protected from oil or dirt. Another object is to provide for the conservation of oil used in the machine, enabling its use in a very simple manner.

The above features, and others contributing to the efficiency of the machine, will be apparent from the following detailed description of a preferred embodiment, as shown in the drawings.

In the drawings, Fig. 1 is a side elevation of my pipe working machine; Fig. 2 is a vertical central longitudinal section of the machine, on a plane parallel with Fig. 1; Fig. 3 is a view looking at the right-hand end of the machine, as shown in Fig. 1; Fig. 4 is a perspective of the combined carriage bed and motor housing; Fig. 5 is a vertical cross-section through the gear housing, as indicated by the lines 5—5 on Fig. 2; Fig. 6 is an elevation of a pipe threader which may be employed, and which is shown in section in Fig. 2.

Briefly, the entire machine comprises a bed 10, having a hollow standard 15, housing a reduction gearing and carrying a driven chuck 20. A motor 30 controlled by a switch 70 is mounted on the bed and connected with reduction gearing within the housing 15; a supplemental bed 40 carried by the bed 10 houses the motor 30 and supports a slideable carriage 80, which carries the tools. The tools shown comprise a threading device 90 and a cutter 100. Mounted on the side walls of the supplemental bed 40 are removable containers 120 for receiving the waste oil. These various parts will now be described in detail.

The bed 10 is a flat member, shown suitably cored on its underside for lightness, and the combined gear housing and chuck standard 15, as shown, is integral with the bed except as to a removable end plate 16 normally bolted in place. At the top, this standard 15 is formed into a semi-

cylindrical seat 17 for the chuck barrel. This bearing is closed above by a downwardly facing and semi-cylindrical cap 18, which carries a centrally and upwardly extending hollow housing 19 for the reception of the upper portion of the main gear.

The chuck 20 is of usual form, comprising a head having radially slideable jaws 21 and a hollow barrel 22 which is rotatably mounted in the bearing 17, 18. The end portion of the barrel is enlarged as at 23, so that longitudinal movement of the chuck is prevented. Centrally of the barrel 22 is an enlargement 24, to which is keyed the main gear 25 driven by the motor through a train of gearing.

The motor 30 is secured on the bed 10 in a position beneath the working space beyond the face of the chuck. The motor has its armature shaft 31 connected by a coupling 32 to a shaft 33 journaled in bearings mounted in the adjacent face of the standard 15. Shaft 33 is shown as having a pinion 34 meshing with an idler gear 35, which carries the pinion 36 meshing with a second idler 37, carrying a pinion 38 engaging main gear 25. This makes a direct train of spur gearing from the motor to the chuck, providing the desired reduction.

Surmounting the motor is a peculiarly formed casting 40, which operates to house the motor and also support the carriage. This casting is shown in perspective in Fig. 4. It comprises four pads or feet 41 adapted to be bolted to the bed, two feet on each side being connected by a vertical web or side wall. At their upper edges the walls 42 extend outwardly as at 43 and then curve inwardly and upwardly to form roof 51. This roof also curves downwardly at its ends and is thus a shallow dome or "turtle-back." At one end this turtle-back unites with a horizontal portion 53. The horizontal floor portion 53 slopes downwardly from the center as indicated at 54 to cause oil, etc. to flow freely toward the sides of the casting; at its outer edge the horizontal floor 53 terminates in an upwardly curving flange 55 which guides oil and chips toward the sides of the casting. Suitable brackets 45 extend from the turtle-back upwardly and are arranged to support horizontal flat strips 46 (Figs. 1 and 3) which provide a slideway for the carriage. A suitable transverse web 47 serves to brace the turtle-back and prevent oil from flowing forwardly of the front carriage supports 45.

It will be seen from Figs. 1 and 2 that the casting 40 above described protects the motor, entirely covering it above and at the front and

back, as well as at the right-hand end of the machine, where the side walls 42 are connected by a transverse web or end wall 48, Fig. 3. The web 48 has an opening to allow access to the motor, 5 but this may be closed by a cover plate, if desired. At the other end the casting 40 is open for the purpose of ventilation.

It will be noted that the inner or left-hand end of the casting 40 is spaced from the upper 10 right housing 15 to provide for ventilation. The controlling switch 10, Fig. 1, is secured to the transverse plate of the standard 15 between such standard and the end of the casting 40 and is electrically connected with the motor so that the 15 latter may selectively rotate in either direction.

The carriage 80 is of the usual type, and rests on the guides 46 of the supplemental frame and is held thereto by suitable gibbs 81 (Fig. 3) extending beneath the overhanging edges of the 20 guides. As shown in Fig. 1, this carriage may be of the form shown in Patent No. 2,079,179, referred to, having upright posts 82 which carry, on the side toward the chuck, the threading device 98, and on the opposite side, the cutter 100. 25 These parts may, if desired, be of the form shown in the prior patent mentioned. As shown herein, they will be briefly described later.

Suitable means are provided for moving the carriage lengthwise of the bed. The means 30 shown comprises a centrally downwardly-facing rack 85, which meshes with pinion 86 on a shaft 87 journaled with bearings 67 carried by the guide bars 46. A suitable hand wheel 88 furnishes means for rotating the shaft to shift the 35 carriage toward and from the chuck, as desired.

Referring to Fig. 6, 90 indicates a suitable ring-like frame carrying radial chasers 91 to coact with the pipe A. The ring 90 is shown as having diametrically opposite horizontal ears 40 92, which seat in ways in the carriage posts and may be held in place by tapered pins 93. As shown, the ring frame 90 carries a face plate 95 having internal cam grooves coacting with pins on the chaser. The ring carries a crank 96 45 operated by hand lever 97 and adjustably connected by a link 98 to the cam plate. Accordingly, the throwing of the lever may spread the chasers or return them, if desired.

The cutter is illustrated in the drawings as of 50 the form shown in the patent referred to, although another form of cutter may be used, if desired. Briefly, in the form shown, the cutter comprises a slideable block 101 (Fig. 3) mounted on one of the carriage posts and carrying a cutting wheel 102. Opposed to this is a slideable block 104 carrying a pair of rollers 105. Rods 106 attached to the block 104 pass slidably through ears on the block 101 to a head 107. Rotatably mounted in this head is a screw-threaded shaft 60 screwing into the block 101 and carrying on its free end an operating hand wheel 109. The turning of this hand wheel may therefore force the blocks toward each other or cause them to recede, as desired.

65 In Figs. 1 and 3, 120 indicates open top containers which are removably supported by and rest against the respective side walls 42 of the supplemental frame 40, the inner side edges of the container coming beneath the overhanging horizontal walls or beads 43 of the frame. Chips and oil dropping from the tools slide off the turtle-back 51 and drop into the containers. 70 Each container may be provided with the usual removable screened basket, not shown.

75 The inner wall of each receptacle 120 is pro-

vided with a pair of bayonet slots 125 adapted to receive respective headed pins 126 secured to the side walls 42 of the supplemental frame 40, thus facilitating the removal of the reservoirs. The inner walls of each reservoir underlie the 5 horizontal portion 43 of the frame 40, the outer edge of which depends slightly as indicated in Fig. 4, at 52, thus insuring the draining of all oil into the reservoirs.

The used oil, together with the discharged 10 chips and dirt will pass downwardly from the turtle-back 40 into the receptacles 120. From time to time the receptacles will be removed and the dirt and chips removed therefrom, then the 15 relatively clean oil may be poured from the receptacle, for instance, into a supply reservoir 130, mounted on a post 131 on the carriage. From this reservoir oil is discharged to the tools through a pipe 135, controlled by a cock 136.

It will be seen from the description given that 20 by employing the peculiar supplemental frame shown and described, I have thoroughly protected the motor, and allowed provision for ventilation thereof. At the same time, I have provided means for readily retrieving the waste oil 25 and restoring it to condition for using. The removable receptacles enable ready transfer of the oil to the supply reservoir without the necessity of employing a pump, thus rendering the whole 30 machine less liable to get out of order.

I claim:

1. In a power driven tool, the combination of 35 a chuck, a motor for driving the chuck, a carriage over the motor adapted to carry a tool for engagement with a pipe mounted in the chuck, a housing over the motor and beneath the carriage having a gutter for receiving oil, and a receptacle carried by the housing, said housing being adapted and arranged to divert oil falling thereon into said receptacle.

2. In a pipe working tool, the combination of 40 a bed, a rotatable chuck supported thereby, a motor geared with the chuck, a hollow supplemental frame mounted on the bed and housing the motor, said supplemental frame also carrying 45 slides for a carriage and having an upwardly open receiving gutter at one end, and a receptacle removably mounted on the supplemental frame and in open communication with said gutter.

3. In a pipe working tool, the combination of a 50 bed, a supplemental frame mounted thereon and having a pair of spaced upwardly extending walls, said supplemental frame having a dome-shaped roof and having means to divert fluid toward the opposite sides thereof.

4. In a pipe working tool, the combination of a 55 bed, a frame mounted thereon and having two pairs of spaced upwardly extending walls, said frame having a roof connecting the inner walls of the two pairs and extending outwardly there- 60 beyond, said frame having also a carriage support, the carriage mounted on said support, a rotatable chuck adapted to carry a pipe coacting with a tool on the carriage, and a motor beneath the roof of the frame geared with the chuck.

5. The combination of a bed, a frame thereon comprising two spaced upright walls, a roof connecting said walls and extending outwardly there- 65 beyond, a removable open topped container supported by said walls and extending beneath the 70 outwardly extending portion of said roof to receive material flowing therefrom.

6. In a pipe working tool, the combination of a bed, a chuck carried thereby, a frame carried by the bed having a pair of spaced walls, a roof 75

connecting said walls, a motor housed between the said walls and beneath the roof, gearing between the motor and chuck, a carriage carried by the frame to carry a tool coating with material in the chuck, and removable containers carried by said walls and positioned externally thereof.

7. The combination of a frame, a hollow standard rising therefrom, a rotatable chuck carried by the standard, a motor mounted on the frame, reduction gearing within the hollow standard connecting with the chuck and motor, a housing carried by the frame having a pair of spaced walls embracing said motor, and a roof connecting with 5 the said walls to cover the motor, a pair of containers removably supported at the sides of said housing, a draining gutter at one end of the housing to divert material into the containers, carriage slides supported by the walls and roof 10 of the housing, and a carriage on said slides.

8. The combination with a bed, of a supplemental frame thereon, said frame having a pair of spaced longitudinally extending side walls and a roof-like portion joining said walls, said roof 15 portion sloping downwardly toward said side walls, a gutter at one end of said roof portion to divert oil toward the side walls of said frame, and means at the other end of said roof portion to prevent the flow of oil from such end of said 20 frame.

9. The combination with a bed, of a supplemental frame secured thereto, said frame having a pair of spaced side walls extending upwardly from said base, and a roof portion joining said 25 walls and sloping downwardly toward said walls and toward the ends of said frame, said roof portion extending outwardly beyond the side walls and being provided with a downwardly extending bead formation, a gutter at one end of said 30 frame and an upstanding bridge at the other end of said frame whereby oil flowing from said roof will be diverted towards the sides thereof.

10. The combination with a bed, of a supplemental frame secured thereto, comprising a pair 35 of spaced side walls extending upwardly and inwardly from said base, and a dome-shaped roof portion joining said walls and extending outwardly therebeyond, and being provided with a downwardly extending bead formation, a pair of upstanding post formations carried by said roof, and at each end thereof, an upstanding bridge wall connecting the posts at one end of said frame and a gutter at the other end of said frame, and means removably carried by said side walls to 40 receive fluid draining from said roof.

11. In a pipe working tool, the combination of 45 a rotatable chuck, a carriage shiftable toward and from the chuck, a motor and transmission mechanism for driving the chuck, said motor being located beneath the carriage, and a downwardly diverging roof over the motor adapted to shed material dropping from the carriage.

12. In a pipe working tool, the combination of 50 a rotatable chuck, a motor for driving the chuck,

a housing over the motor having a downwardly sloping roof-like portion adapted to shed material, a pair of guide bars secured to the housing in a manner leaving openings beneath the guide bars and above the roof, and a carriage slidable on 5 the guide bars toward and from the chuck.

13. In a machine of the character described, the combination of a rotatable chuck, a carriage shiftable toward and from the chuck, a motor and transmission mechanism for driving the chuck, said motor being located beneath the carriage, a roof over the motor, posts extending upwardly from said roof, and guides for the carriage mounted on top of the posts.

14. The combination of a rotatable chuck, a 15 motor for driving the chuck, a housing over the motor having a roof-like portion adapted to shed material, a pair of guide bars secured to the housing, a carriage slidable on the guide bars toward and from the chuck, each guide bar carrying an 20 eye at its end, a rotary shaft mounted in said eyes, and gearing connecting said shaft to the carriage.

15. In a tool of the character described, the combination of a bed, a standard carried thereby, 25 a rotatable chuck carried by the standard, a motor on the bed, gearing connecting it with the chuck, and a supplemental frame mounted on the bed and removable independently of the standard, the motor and the gearing and providing a 30 housing in front and behind and over the top of the motor and providing also a support for the carriage.

16. The combination of a bed, a standard thereon with a removable cap providing a bearing, a 35 chuck having a barrel rotatably journaled in said bearing, a frame carried by the bed and comprising upright walls supporting a dome-like roof, said frame having also horizontal slideways supported above the roof in a manner leaving 40 openings beneath the slideways and above the roof, a carriage on the slideways at an elevation to cooperate with the chuck, and a motor beneath the roof geared with the chuck barrel.

17. In a pipe working tool, having a motor-driven chuck and a tool-supporting carriage, the employment of a combined protecting hood for the motor and support for the carriage above the motor, said hood having its top formed to shed oil to the exterior, and a receptacle removably 50 held on the hood below the edge of said top in position to receive said oil.

18. In a machine of the character described, the combination of a bed, a frame thereon having a roof downwardly inclined toward the front and 55 rear and having upstanding portions spaced apart and located adjacent the ends of the inclines, slideways for the carriage mounted on the upstanding portions and leaving unobstructed spaces beneath them and above the roof, a carriage on the slideways, a motor beneath the roof, and a chuck driven by said motor.

WILLIAM A. PHILLIS.
